UNITED STATES PATENT OFFICE.

WILLIAM S. ELLIOT AND WILLIAM NOBLE, OF NORTHAMPTON, MASSACHUSETTS, ASSIGNEES TO PRO-PHY-LAC-TIC BRUSH COMPANY, OF NORTHAMPTON, MASSACHUSETTS, A CORPORATION OF MASSACHUSETTS.

BRUSH-MAKING MACHINE.

Application filed February 24, 1925. Serial No. 11,090.

This invention relates to brush machines of the type shown in the patent to Schwartz No. 1,125,187, dated January 19, 1915, and has particularly to do with the mechanism 5 for feeding the ribbon of metal to the punch which forms the anchors and for actuating the pusher which sets the anchors after they have been formed by the punch. Since the anchor is minute, extreme accuracy is required and in machines as heretofore constructed, difficulty has been experienced with mechanism for these purposes since the mechanism has been complicated.

The object of the present invention is, 15 therefore, to provide simple mechanism for operating the grippers which feed forward the ribbon to the punch and that which operates the pusher which sets the anchors. Also to provide mechanism which will permit the machine to be run at much increased 20 speed without loss of accuracy.

Accordingly in the machine embodying the present invention we have devised a combination of cams which are rotated 25 constantly and which give to the several mechanisms rapid and easy motions and which, on account of the simplicity of the construction, is not affected by wear so that the accuracy of the machine remains the same.

The invention will be fully understood 30 from the following description when taken in connection with the accompanying drawings, and the novel features thereof will be pointed out and clearly defined in the claims 35 at the close of this specification.

In the drawings.

Fig. 1 is a top plan view.

Fig. 2 is a front elevation of the parts shown in Fig. 1.

Fig. 3 is a section taken on line 3—3 of Fig. 1.

Referring to the drawings:

At A is shown the punch, at B the bristle reservoir, at C the nose of the plunger or tufter and at D a strip of metal from which the anchors are cut. The metal ribbon D is fed forward into the punch by a pair of swinging grippers E and F. The tufter is mounted on a slide H, the pusher which sits 45 on the anchors being shown at I. At K is shown the notched needle which enters the bristle reservoir B and separates the proper 50 number of bristles to form the tuft carrying it to the channel in the tufter. The parts heretofore described are old and well known being substantially as shown in the patent to Schwartz already mentioned. The pusher, plunger slide, strip feed and needle all co-operate with each other and therefore must be positioned and timed with extreme accuracy to enable the machine to be run at high speed.

The feeding mechanism for the strip D and operating mechanism for the pick K will now be described. The strip is fed by 65 the upper and lower grippers E and F respectively. The upper gripper E is pivoted at G to the frame of the machine, and is caused to swing about the pivot a sufficient amount to advance the strip the required 70 distance. The movement of the upper gripper is produced by the surface *a* on a cam 14 mounted on a constantly running shaft 15 driven by a sprocket 16. The cam acts through a slide 11 which carries a cam-roll 75 10 at one end thereof, the other end being connected by a link 12 to a lug 13 on the upper gripper E.

This cam also is provided with a groove *b* to receive the cam roll 17 which operates the 80 pick K. The cam 14 is therefore in effect two cams, one of which operates the strip feed, and the other of which moves the pick, thereby supplying bristles to the tufter. The cam roll 17 is carried on the end of a 85 lug forming part of a slide 18 to which the rear end of the pick K is adjustably attached by means of screws 19 and 20. At 9 is shown screw actuated mechanism for adjusting lengthwise the position of the pick relative 90 to the cam. By this means a very fine adjustment of the needle can be made so that the notch therein will be in exact registration with the channel through the plunger tube and thereby the certain transfer of the 95 tufter bristles from the notch in the pick to the tufter will be assured. The lower gripper F is connected by a ball and socket joint, as shown at 80, with one arm of a bell-crank 21 pivoted at 22 and having on its lower end 100 a cam roll 23. This cam roll rests against a cam 24 carried on a shaft 25 which is driven in proper time with the other parts of the machine.

Referring now to the mechanism for operating the tufter or plugger C and pusher I, there is shown in Fig. 1 a shaft 26 which is also constantly driven by a sprocket 34. This shaft carries a plate cam 27 having a groove in the face thereof. The walls of this groove engage a roller 28 carried on one end of an arm 29 which is upwardly curved and offset, as shown in Figs. 1 and 3. The other end of this arm is connected by pins 30 and 31 to the rear end of the plugger slide H. Nuts 32 and 33 are provided to adjust the position of the plugger slide relatively to the arm 29 and consequently to the cam 27. In this way the limit of forward movement of the nose of the plugger or tufter can be adjusted. The sprocket 34 which drives the shaft 26, also acts as a crank disk to actuate a connecting rod 35, the front end of which is connected to a lever 36 which carries a bearing pin 37 for the rear end of the pusher I. These parts move in a slot 38 in the plugger slide which is cut away as shown in the drawings to give the necessary clearance. It will, therefore, be seen that as the shaft 26 is rotated the plugger slide H will be reciprocated being given the motion by the layout of the cam 27 and that simultaneously the pusher will be reciprocated by the sprocket or crank disk 34 and that both the

plugger slide and pusher will have smooth and easy motions enabling the machine to be run at high rates of speed. It will also be seen that the construction of the operating mechanism for the strip feed, needle, plugger slide and pusher do away with the springs and long levers which in the original Schwartz machine limited the speed of the machine and diminished its accuracy and that on the contrary all of the parts are moved positively by smooth mechanisms which are capable of operating at very high rates of speed without pounding or excessive wear or affecting the accuracy of the operation of the machine.

What we claim is:

1. A brush making machine comprising a reciprocating slide, a pick carried by said slide for separating a tuft of bristles, and a rotary cam coacting directly with said slide for operating the same.

2. A brush making machine comprising a rotary cam, a gripper for feeding an anchor forming metal strip, and a slide connected to said gripper and operated by said cam.

In testimony whereof we affix our signatures.

WILLIAM S. ELLIOT.
WILLIAM NOBLE.
